UNITED STATES PATENT OFFICE.

FERDINAND DE CRAIG MARTIN, OF BILOXI, MISSISSIPPI.

FINGER-GUARD FOR SEWING-MACHINES.

1,091,363.

Specification of Letters Patent. Patented Mar. 24, 1914.

Application filed June 26, 1913. Serial No. 775,881.

To all whom it may concern:

Be it known that I, FERDINAND DE CRAIG MARTIN, a citizen of the United States, residing at Biloxi, in the county of Harrison and State of Mississippi, have invented certain new and useful Improvements in Finger-Guards for Sewing-Machines, of which the following is a specification.

This invention relates to presser foot attachments for sewing machines, and pertains especially to a finger guard made with, formed on, or attached to the presser foot and hemmer, or other foot of a sewing machine.

15 The object of the invention is to provide the ordinary presser foot and hemmer foot with a finger guard of such novel and peculiar shape or construction as to prevent the fingers of the operator coming in contact 20 with the machine needle, during the operation of the machine.

A further object of the invention is to provide a finger guard of such novel and peculiar construction relative to a hemmer or 25 presser foot as to permit the sewing thread to be grasped and pulled as usual, and having such shape as not to obscure or obstruct the view of the working needle and the stitching or hemming work.

30 In the accompanying drawings forming part of this application:—Figure 1 is a perspective view showing the application of the invention. Fig. 2 is a top view of a presser foot showing the guard. Fig. 3 is a front view of the guard and presser foot. Fig. 4 is 35 an inverted perspective view of a presser foot and guard. Fig. 5 is a perspective view of a modification.

The same reference characters denote the 40 same parts throughout the several views of the drawings.

The sewing machine table 1, head 1^a, needle 2, bar 2^a, the presser foot bar 3, and the attachment for the presser foot 4 are 45 such as may be found in common use, and are only employed to exemplify the invention.

The presser foot 4 is of the usual shape and construction, having a short prong 5,

and a long prong 6, with the needle slot 7 between the prongs.

The guard is substantially U-shaped and comprises a flange 8, formed on or soldered to the outer edge of the prong 6, and projecting vertically therefrom, a continuation of 55 the flange 8 extends around the end of the prong 6 so as to form a vertical bowed front portion 9, and a curved wing 10 projects inwardly from the bowed portion 9. The wing 10 is tapered or increases in width 60 from its juncture with the bowed portion 9, so as to form a wide or flaring end 11, and a sight space or opening 12, at the front of the guard and between the prong 5 and the wing. The edge 13 of the bowed portion 9 65 extends vertically from the inner edge of the end of the prong 6 to the juncture of the bowed portion 9 and the wing 10, so that the view of the needle and the material under operation is not obscured or interfered with, 70 and so that the operator may readily catch the thread close up to the foot without interference of the guard. The flared portion of the wing over-laps the end of the prong 5 and terminates above said end in the same 75 plane with the rear edge of the flange 8, so as to leave a space or opening between the attaching arm 14 of the presser foot and the rear edge of the wing and the flange, whereby the work and the thread may be viewed 80 and operated as usual.

Referring to the modification shown in Fig. 5 the guard 15 extends across the face of the hemmer foot 16, in front of the path of movement of the needle, and has inturned 85 ends. Said guard is connected with and held above the foot by means of a vertical guard portion 17, so as to leave an opening or space 18 between the foot and the guard.

It is obvious that the invention may be 90 further modified mechanically for use on presser feet of various character, and that the guard and foot may be made together, or the guards may be made separately and soldered or otherwise attached to the feet 95 in common use.

I do not wish to be understood as confining the invention to any particular size or

material, nor to any particular presser foot of sewing machines, but reserve to myself the right to make such changes in the guard and its application as may come within the 5 scope of the appended claim.

Having thus described my invention what I claim as new and desire to secure by Letters Patent is:—

A finger guard for the presser foot of 10 sewing machines, comprising a flange

formed on one side of the foot, and a wing bowed from the upper portion of the flange across the front of the foot and terminating in a free end above the foot.

In witness whereof I hereunto set my 15 hand in the presence of two witnesses.

FERDINAND DE CRAIG MARTIN.
